CLAIM

The ornamental design for a detail bucket assembly, as shown and described.

DESCRIPTION

FIG. 1 is a perspective view of the detail bucket assembly; FIG. 2 is a front view of the detail bucket assembly; FIG. 3 is a right elevation view of the detail bucket assembly;

FIG. 4 is a rear view of the detail bucket assembly;

FIG. 5 is a left elevation view of the detail bucket assembly; FIG. 6 is a top view of the detail bucket assembly; and,

FIG. 7 is a bottom view of the detail bucket assembly. The shade lines in the Figures show contour and not surface ornamentation.

The broken lines showing portions of the design in all figures are included for the purpose of illustrating environment and do not form a part of the claimed design.
